UNITED STATES PATENT OFFICE.

JOHN H. MEREDITH, OF ST. ANTHONY, IDAHO.

PUZZLE.

1,245,942.

Specification of Letters Patent.

Patented Nov. 6, 1917.

Application filed December 29, 1916. Serial No. 139,574.

To all whom it may concern:

Be it known that I, JOHN H. MEREDITH, a citizen of the United States, residing at St. Anthony, in the county of Fremont and 5 State of Idaho, have invented new and useful Improvements in Puzzles, of which the following is a specification.

This invention is a puzzle to afford amusement and interest and which is also adapted 10 for use as an advertising device.

The invention consists in the construction, combination and arrangement of devices hereinafter described and claimed.

In the accompanying drawings:

15 Figure 1 is a perspective view of a puzzle constructed and arranged in accordance with this invention.

20 Figs. 2 and 3 are similar views of the same showing the parts in different positions and illustrating the manner in which the loop string is released from the member which is provided with the eye.

25 The puzzle consists essentially of a member 1 having an eye 2; a cord 3 having a loop 4, and a member 5 attached to the cord.

The member 1 may be of any suitable construction and is here shown as a rod of suitable length. The member 5 may also be of any suitable construction but is preferably 30 a disk, star, medallion, shield or the like and in practice may be inscribed with advertising matter.

Normally the loop of the cord is passed 35 through the eye of the member 1 and the other end of the cord is passed through the

loop so that the member 5 is connected to the eye 2 by the cord 3. The problem presented by the puzzle is to entirely disconnect the cord from the member 1 without untying or cutting the cord. This is done by first 40 slipping the cord loop 4 over the eye as shown in Fig. 1 and then passing the loop over the outer end of the rod 1 as shown in Fig. 2 and thus enabling the cord together with its loop to be drawn out entirely from 45 and through the eye 2 as will be understood.

To rearrange the puzzle the loop is first passed through the eye then end of rod is 50 passed through the loop and loop drawn upward and around the rod to the eye and is then passed over the eye, thus forming a bight which connects the cord to the eye.

While I have herein shown and described the preferred form of my invention I would have it understood that changes may be 55 made in the form, proportion and construction of the several parts without departing from the spirit of my invention, and within the scope of the appended claim.

Having thus described the invention what 60 is claimed is:

A puzzle comprising a rod having an eye at one end, a cord of greater length than the rod and having a loop at one end arranged to be passed through and slipped 65 over the eye, and a member of a width greater than the diameter of the eye and attached to the other end of the cord.

In testimony whereof I affix my signature.

JOHN H. MEREDITH.
